UNITED STATES PATENT OFFICE.

HANS TECHEL, OF KIEL, GERMANY, ASSIGNOR TO FRIED. KRUPP AKTIENGESELLSCHAFT GERMANIAWERFT, OF KIEL-GAARDEN, GERMANY.

SUBMARINE BOAT.

1,183,695.

Specification of Letters Patent. Patented May 16, 1916.

Application filed February 3, 1914. Serial No. 816,225.

To all whom it may concern:

Be it known that I, HANS TECHEL, a citizen of the German Empire, residing at Kiel, Germany, have invented certain new and useful Improvements in Submarine Boats, of which the following is a specification.

This invention relates to submarine boats, which are provided with an apparatus for laying mines. In known boats of this kind the mines are mounted on deck in laterally arranged open cells, the bottoms of which are inclined, and out of which the mines can automatically slide into the water after the release of the retaining devices. This arrangement of the mines is very unfavorable and dangerous, inasmuch as the mines, owing to the short path of descent traversed when they slide off, have only a comparatively low velocity imparted to them, and therefore when sliding off the said mines may easily strike against the hull of the boat or, if they are already in the water, and sliding along the hull of the boat, may be struck by the screw.

The object of the present invention therefore is to provide a submarine craft of the kind hereinbefore mentioned, in which the mines can be so brought into the water, that all danger of injurious contact of the said mines with any part of the craft is avoided.

A constructional example of the subject matter of the invention is illustrated in the drawing in which—

Figure 1 is a vertical longitudinal section 35 of a submarine boat constructed according to the invention. Fig. 2 is the plan view corresponding to Fig. 1 and Fig. 3 is a section on the line 3—3 of Fig. 1 looking from the left, while Figs. 4 and 5 show details on a 40 larger scale.

A is the thin-walled outer hull and B the pressure proof inner hull of the submarine boat. The mines C are so arranged that they can be thrown out over the stern of the boat. 45 For this purpose they are arranged to travel in two longitudinal rows in channels D in the non-water tight platform of the boat. The wheels of the underframe E of each mine, which is at the same time constructed 50 to act as a mine anchor, run in U-shaped guide rails F.

The traveling mines are transferred and ejected by endless chains J and K, the latter chains K being arranged in pairs for each

row of mines. The chains are passed over 55 rollers L M and N O respectively and can be driven by a motor S mounted in the interior of the boat. The chains J and K are driven at different speeds, so that the longer or transferring chains J are driven slowly 60 and the shorter or ejecting chains K rapidly. This is accomplished in the present case by making one and the same shaft Q drive the chains J through a worm wheel gearing R and the chains K through a bevel wheel 65 gearing P.

At fixed intervals, determined by the length of the mines, the pivot bolts of the chains J and K are extended on both sides and in this way fashioned into tappet bolts 70 i^1 and k^1 , into the path of which latter fork-shaped stops G and H on the under frame of the mine project (see particularly Figs. 4 and 5). Clutches U and V (see Fig. 2) which can be thrown into and out of operation from the interior of the boat, enable one set of chains (the one on the port side in the present case) to be stopped. In order to compensate the weight of the boat and the trimming moment, which change with 75 80 the throwing out of the mines, two ballast tanks W¹ W² are employed of which the former is arranged amidships and the other in the rear part of the ship.

The action of the above described apparatus is as follows: When commencing to lay the mines, the clutches U V are thrown out of operation, so that on starting the motor S only the chain drives J K on the starboard side are set in motion. Under 90 these circumstances the tappets i^1 on the chain J propel or transfer, by means of the stops G, the row of mines slowly in the direction of the arrow x (see Fig. 1) toward the stern of the boat. When the first 95 mine carriage has advanced so far that its front wheels are located over the chains K, the tappets k^1 on these chains engage with the stops H on the mine carriage and in consequence of the greater peripheral 100 velocity of the chains K, impart to the mine such a speed that it is thrown outward clear of the stern of the boat, without striking against the latter.

From the foregoing, it will be seen that 105 the invention embodies a slow conveyer for transferring the mines from a receiving point to a delivery point which is near the

point of ejection, and a fast conveyer which takes the mines from the transferring conveyer at or near the point of delivery and ejects them into the water. It will also be seen in the illustrative embodiment that the mines are mounted upon carriages upon which they are adapted to travel in the channels or storage means to the point at which they are received by the transferring conveyer.

The speeds of the endless chains J K, and the speed at which the boat is traveling, must be so arranged that the mines are deposited in the water at the proper intervals for an effective mine blockade. As soon as the last of the mines has been thrown overboard in this way on the starboard side of the ship, the clutches U V are thrown into operation, after which the mines carried on the port side are thrown out in the same way. While this is being done the endless chains on the starboard side may run idly therewith, if no special device for throwing them out of operation is provided.

The compensation of the weight and moments is effected in the well known way, by means of the tanks W¹ W², and the inlet of the water into these tanks is so regulated, that immediately before a mine is thrown out both the weight and the trimming moment are approximately compensated. Any slight differences in trimming still present can be easily compensated by the diving rudders of the boat. When all the mines have been thrown overboard, perfect compensation of weight and moments must exist.

In order to prevent the shocks which arise, when the tappets Z engage with the stops H, from acting injuriously on the mines and on the motor S, it is advisable to make the clutch V or the spur wheel gearing elastic, e. g. to arrange it elastically on its driving shaft.

It is obvious of course that more than two rows of mines may be arranged on the deck of the boat. Under some circumstances also the mines may be thrown out by a single ejecting apparatus K, placed amidships and in front of which the rails of the several rows of mines converge after the manner of switches. The formation of the under frame of the mines is also of subsidiary importance to the invention. Instead of the box-like frames provided with wheels and running on rails, sledge-shaped under-frames might be used for example, running on suitable runners.

The above described mounting of the mines in the outwardly closed channels D, affords in comparison with the known arrangement of the mines in laterally open cells, the advantage that the mines are protected from shocks, and that the resistance of the boat to the water is, owing to the

smooth upper surface of the platform, not substantially greater than that of a normal submarine boat.

If when laying a close mine blockade, both rows of mines are to be simultaneously brought into the water, the arrangement of the mines must be such that those on the port side are displaced relatively to those on the starboard side by half the length of a mine, so that a port and a starboard mine are alternately brought into the water without there being any fear of a collision between the mines.

I claim:

1. Apparatus for laying out mines from boats, said mines having rollers, comprising tracks for the rollers, a conveyer adapted to receive the mines and transfer them along said track to a delivery point, and a separate conveyer adapted to take the mines at said delivery point and eject them.

2. Apparatus for laying out mines from boats, said mines having rollers, comprising a track for said rollers, said track running in longitudinal direction of said apparatus, a slow conveyer adapted to carry the mines along said track and transfer them to a delivery point, and a fast conveyer adapted to take the mines from the transferring conveyer at said delivery point and eject them into the water.

3. Apparatus for laying out mines from boats, comprising a plurality of means adapted to receive and store the mines, a plurality of conveyers adapted to receive the mines from the respective storing means and transfer them to a delivery point, and a plurality of relatively faster conveyers adapted to receive the mines from the transferring conveyers at the delivery points and eject the mines into the water.

4. Apparatus for laying out mines from boats, comprising a conveyer adapted to receive the mines and transfer them to a delivery point, and a separate conveyer operating with greater speed than said first conveyer and adapted to take the mines at said delivery point and eject them, said conveyers being provided with tappets adapted to engage the mines.

5. Apparatus for laying out mines from boats, comprising mine carriages constructed with stops adapted to be engaged for propelling said carriages, a conveyer running at a certain speed and constructed with tappets adapted to engage with the stops on the mine carriages and transfer said carriages with their contained mines from a receiving point to a delivery point, and a separate conveyer running at increased speed and adapted to eject mines from the transferring conveyer after they reach the delivery point.

6. Apparatus for laying out mines from boats, comprising mine carriages con-

structed with stops adapted to be engaged for propelling said carriages, a conveyer constructed with tappets adapted to engage with the stops on the mine carriages and transfer said carriages with their contained mines from a receiving point to a delivery point, and a separate conveyer adapted to eject mines from the transferring conveyer after they reach the delivery point; the ejecting conveyer being also provided with tappets through which it is adapted to engage the stops on the mine carriages in effecting ejection of the mines at greater speed than that at which the transferring

conveyer is running.

7. Apparatus for laying out mines from boats, comprising a plurality of means adapted to receive and store the mines, a plurality of conveyers adapted to receive the mines from the respective storing means and transfer them to a delivery point, and a plurality of relatively faster conveyers adapted to receive the mines from the transferring conveyers at the delivery points and eject the mines into the water; suitable driving mechanism serving in common for the different transferring conveyers, and means for throwing said driving mechanism into

operative relation with either of said transferring conveyers at will.

8. In combination with a submarine boat, apparatus for laying out mines therefrom embodying longitudinal channels presented in position to deliver mines from the stern of the boat into the water, and having means for propelling mines at a certain speed from said channels and other means running at a higher speed than said propelling means for ejecting the mines into the water.

9. The combination with a submarine boat having a hull with a pressure proof portion and a deck outside the pressure proof portion, and means for storing and laying out mines from said boat comprising channels located on said deck outside the pressure proof portion of the hull, and means for propelling and ejecting mines from said channels.

In testimony whereof I affix my signature in presence of two witnesses.

HANS TECHEL.
